UNITED STATES PATENT OFFICE.

RICHARD K. GREGORY, OF GREENSBORO, NORTH CAROLINA.

WHEEL.

No. 902,072.

Specification of Letters Patent.

Patented Oct. 27, 1908.

Application filed March 16, 1907. Serial No. 362,706.

To all whom it may concern:

Be it known that I, RICHARD K. GREGORY, citizen of the United States, residing at Greensboro, in the county of Guilford and 5 State of North Carolina, have invented certain new and useful Improvements in Wheels, of which the following is a specification.

This invention has for its object an improved construction of wheel which depends for its resiliency upon a series of springs, and not upon rubber, or cushion or pneumatic tires, and which will possess all of the characteristics of resiliency of the cushion 15 and pneumatic tire type of wheel without the liability to puncture and wear incidental thereto, and which will also possess characteristics of extreme durability and lightness combined with strength and be comparatively cheap to manufacture, assemble, and maintain.

With these and other objects in view as will more fully appear as the description proceeds, the invention consists in certain 25 constructions, arrangements and combinations of parts which I shall hereinafter fully describe and then point out the novel features in the appended claim.

For a full description of the invention and 30 the merits thereof and also to acquire a knowledge of the details of construction of the means for effecting the result, reference is to be had to the following description and accompanying drawings, in which:

35 Figure 1 is a side elevation of a wheel embodying the principles of my invention; Fig. 2 is a side elevation of a portion of the wheel, on an enlarged scale, partly in section; Fig. 3, is a transverse sectional view 40 of the wheel; Fig. 4 is a detail side elevation of one of the blocks or shoes hereinafter specifically referred to; and, Fig. 5 is a detail perspective view of one of said shoes illustrating a modified or alternative form of 45 anti-friction device that may be employed.

Corresponding and like parts are referred to in the following description and indicated in all the views of the drawings by the same reference characters.

50 Referring to the drawings, the numeral 1 designates the hub of the wheel, 2 the spokes thereof, and 3 the felly, all of which may be of any desired construction and design.

4 designates a preferably metallic channeled rim which is secured to the felly in 55 any desired way, and which is formed with

inturned edges providing inwardly facing shoulders 5.

Within the channeled rim 4 is a circumferentially extending series of blocks or 60 shoes 6 which may be composed of wood or any desired composition and which are guided with a radially sliding movement within said channeled rim. They are arranged end to end. Within the rim, each 65 block is formed at its opposite sides with sockets 7 in which anti-friction devices 8 are mounted, said devices being in the form of balls as indicated in Figs. 2, 3 and 4; or they may be in the form of rollers 8^a 70 mounted in longitudinally extending slots 7^a, as indicated in Fig. 5. These anti-friction devices may bear not only between the side edges of the blocks and the adjacent walls of the rim, but if desired they may 75 bear against the meeting ends of the blocks or shoes 6, as indicated in Fig. 5. The sockets to receive the balls or rollers in the sides of the shoes 6 are formed in transverse enlargements 9, the outer edges of which 80 constitute outwardly facing shoulders 10 adapted to coact with the inwardly facing shoulders 5 of the rim to limit the outward movement of the shoes.

To produce the desired resiliency, each 85 shoe 6 is formed in its inner face with one or more sockets 11 (two being shown in the present instance) and a helical spring 12 is seated in each socket and bears against the bottom thereof and against the bottom of 90 the channeled rim 4. Preferably each spring is provided with a core the ends of which bear against the bottom of the socket and the rim, and which may be composed of rubber or other resilient substance. In the 95 drawings these cores are designated 13.

14 designates the tire which may be composed of any desired substance or composition possessing wearing qualities, and it is not essential that the tire be resilient, as the 100 resiliency is provided for by means of the springs 12, with or without the cores 13. As one connection between the tire and the shoes that may be employed, I have shown the tire as formed with a bead 15 fitting 105 within a correspondingly shaped socket in the series of shoes 6.

It is preferred that a guiding connection be provided between the several shoes of the series, and for this purpose I may employ integral tongues 16 projecting from one end of the respective shoes and slidingly

mounted in a corresponding groove 17 in the opposite end of each shoe.

From the foregoing description in connection with the accompanying drawings, it will be seen that I have provided a cheap, simple, durable, and efficient construction of vehicle wheel in which no cushion, pneumatic, or other rubber tire is used while the characteristic of resiliency is retained and the wearing qualities enhanced, while the susceptibility to puncture and other disadvantageous features of a pneumatic-tired wheel are avoided.

Having thus described the invention, what is claimed as new is:

In a vehicle wheel, the combination with a channeled rim and its support, and a circumferentially extending series of shoes movable within said rim and spring pressed outwardly and formed with transversely enlarged inner ends producing outwardly facing shoulders, the rim being formed with coacting shoulders to limit the outward movement of the shoes, the sides of said en-

largement being formed with sockets, each shoe being formed at one end with spaced sockets in line with the sockets of the enlargements and between said end sockets with a groove, each being formed at its opposite end with a tongue of less width than the shoe and in alinement with the side enlargements, said tongue being adapted to fit in the groove of the next adjoining shoe, antifriction devices mounted in the sockets of the side enlargements of the respective shoes and bearing against the sides of the rim, and other antifriction devices in the end sockets at opposite sides of the grooves, said last named antifriction devices bearing against the end of the respective adjacent shoes.

In testimony whereof I affix my signature in presence of two witnesses.

RICHARD K. GREGORY. [L. s.]
